DUPLEX CONDIMENT HOLDER AND DISPENSER

John L. Lyons, North Hollywood, Calif.

Application August 12, 1947, Serial No. 140,829

Term of patent 7 years

(Cl. D44—22)

To all whom it may concern:

I, John L. Lyons, a citizen of the United States residing at North Hollywood, county of Los Angeles, State of California, have invented a new, original, and ornamental Design for Duplex Condiment Holder and Dispenser, of which the following is the specification, reference being had to the accompanying drawings, constituting a part thereof.

Fig. 1 is a side elevation of a duplex condiment holder and dispenser, showing my new design;

Fig. 2 is an end elevation thereof, as viewed from either end;

Fig. 3 is a side elevation thereof, showing the two end cover members separated from the body portion;

Fig. 4 is an end elevation thereof, with the near end cover member removed (and not shown), as viewed from either end; and

Fig. 5 is a three-quarter exploded perspective view thereof.

I claim:

The ornamental design for a duplex condiment holder and dispenser, substantially as shown.

JOHN L. LYONS.
